UNITED STATES PATENT OFFICE.

EDWARD HAROLD SHOVE, OF WESTVILLE, CONNECTICUT, ASSIGNOR TO THE AMERICAN STEEL AND WIRE COMPANY OF NEW JERSEY, A CORPORATION OF NEW JERSEY.

ROPE-STRANDING MACHINE.

Application filed August 27, 1927. Serial No. 215,861.

This invention relates to stranding machines for stranding wire cables and the like, and more particularly to stranding machines of the planetary type, and has for its object 5 the provision of a machine of this type having a novel construction whereby a machine may be provided having more than three bays in each unit and may be operated at a materially faster speed than machines of the 10 planetary type heretofore in use.

Planetary stranding machines as heretofore constructed have generally been limited to a maximum of two bays in each unit due to the manner in which the spool carriers or 15 cradles were mounted and, therefore, it was necessary to build the two bays of considerable diameter in order to carry the eighteen or more spools, and this great diameter, together with other features of their construction, necessitated a comparatively slow rotation for the machine and necessarily limited 20 their production over a given time.

In the accompanying drawings I have illustrated one embodiment of my invention as 25 applied to one unit of a stranding machine and it will be understood that two or three, and sometimes more, such units are set end for end and combined to form one machine. However, since said units are duplicates of 30 each other, illustration of one unit is thought to be sufficient.

Figure 1 is a partial side elevation of a stranding machine constructed in accordance with this invention.

Figure 1^a is a continuation of the side elevation continued from the line X—X of Figure 1.

Figure 2 is an enlarged side elevation of the rear end portion of the machine, partly 40 in section.

Figure 3 is an enlarged side elevation of the central portion of the machine, partly in section.

Figure 4 is an enlarged side elevation, partly 45 in section, of the forward part or head end of the machine.

Figure 5 is a transverse sectional elevation taken on the line V—V of Figure 2.

Figure 6 is a transverse sectional elevation 50 taken on the line VI—VI of Figure 4.

Figure 7 is a schematic plan illustrating the spiral arrangement of the cradles or spool holders.

Referring more particularly to the draw-

ings, the numeral 2 designates the base of the 55 unit and the numerals 3 and 4 designate the entering and discharge or twisting-end housings, respectively.

A shaft 5 extends the entire length of the 60 machine and is journaled in suitable bearings in the end housings 3 and 4. The housing 3 at the entering end of the unit is hollow and forms a housing for suitable drive gearing 6. Power is adapted to be delivered to the shaft 5 through the gearing 6 from a 65 motor (not shown). The twisting-end housing 4 has an extension 7 on which the die 8 is slidably mounted and adapted to be moved by a screw rod 9 having a hand-wheel 10.

A series of seven circular spider members 70 12 are keyed to the shaft 5 in spaced relation to each other and the spaces between said spiders form what is known in the art as "bays". Three-strand spool holders or 75 cradles 13 are mounted at equally spaced intervals in each of said bays with their trunnion ends 13^a journaled in suitable bearings 14 mounted in bearing openings 15 in the spider members at either side of the bay.

The spool holders or cradles in each successive bay from the rear or entering end bay 80 forwardly are offset an equal distance in the same direction relative to the spool carriers in the preceding bay, so that said spool carriers define a spiral path around said central shaft 5 from end to end of said unit.

The rear trunnion ends 13^a of the spool carriers 13 in the rear or entering end bay project beyond the rearmost spider 12 and are 85 keyed to one end of crank-arm members 16, 90 which members have their other ends journaled in bearings 17 mounted in a crank-ring 19 which has a center of rotation below the center of rotation of said central shaft a distance equal to the length of said crank 95 members 16. A pair of hold-down rollers 20 are journaled on stub-shafts 21 mounted in the end housing 3, and project into and engage the lower portion of the crank-ring 19 so as to compel it to maintain its off-center position 100 during the revolving of said unit.

The forward trunnion ends of the spool carriers 13 in the rear bay project beyond the spider 12 in which they are journaled and carry pinions 22 which mesh with idler-pinions 23, and the idler-pinions 23 mesh with pinions 24 secured to the rear trunnion ends 105 of the spool carriers in the next bay, which

spool carriers are offset relative to the spool carriers in the rearmost bay as previously described.

The forward trunnion ends of the spool carriers in the second bay are provided with the gear connection described above, which connects them to the next forwardly succeeding set of spool carriers, and each successive set of spool carriers is similarly connected to the preceding ones in a similar manner.

The foremost set of spool carriers 13 have their forward trunnion ends 13^a projected beyond the foremost spider and are provided with a pinion 26 which is keyed thereto. The pinions 26 are meshed with idler pinions 27, which are in turn meshed with pinions 28 keyed to shafts 29 having their rear ends journaled in bearings 30 in the foremost spider 12 and their forward ends journaled in bearings 31 in a spider bearing ring 32 keyed to the center shaft 5.

The forward ends of the shafts 29 project beyond the bearing ring 32 and are keyed to one end of crank-arm members 33, which crank-arm members have their other ends journaled in bearings 34 mounted in a crank-ring 35, which ring has a center of rotation below the center of rotation of said central shaft 5 a distance equal to the length of said crank-arms 33. A pair of hold-down rollers 34^a are journaled on stub-shafts 35^a mounted in the end housing 4 and project into and engage the crank-ring 35 to compel it to travel in offset position during the rotation of said unit.

The crank-arm members 33 and the crank-arm members 16 and crank-rings 19 and 35 co-operate to swing or rotate the strand carriers or cradles so as to maintain their transverse axis in a horizontal position throughout the rotation of the unit. If, for any reason, either one of the crank-rings 19 or 35, or their associated parts, should become broken, the other set of cranks and ring will serve to operate the strand carriers or cradle.

The strand spool carriers or cradles 13 have an annular body portion which is slotted at each side as at 38 to form bearing slots in which spools 39 carrying the strand wires of the cable are journaled. The forward trunnion end 13^a of each strand spool carrier is provided with a centrally arranged aperture 40 through which the strand wire from the spool in said carrier is threaded so as to project into the next bay.

A sheave supporting collar 41 having three sheaves 42 thereon is secured on the shaft 5 at a point between the bearing-ring 32 and crank-ring 35, and also at approximately the center of each bay except the rearmost bay. The strand wires from the spools 39, after passing through the forward trunnion ends 13^a of the carriers 13, are adapted to be passed under the sheaves 42 in the next bay, and then to be passed parallel to and in close

proximity to the shaft 5. Suitable openings 43 and 44 are provided in each of the spiders 12 and sheave collars 41, respectively, through which the strand wires are threaded and passed to the forward end of the unit.

The shaft 5 is hollow or bored throughout its length to permit the passage of a core strand therethrough as previously described and a twister head 45 is mounted at the forward end of the shaft 5 and is adapted to twist the strand wires on the core in the usual manner. The twister head is provided with a centrally arranged aperture through which the core strand is passed.

The strand wires are passed through the apertures 40 in the forward trunnion ends 13^a of the spool carriers 13 and then trained downwardly and under the sheaves 42 and then parallel with the shaft 5, as previously described. At the forward end of the shaft 5 the strand wires are trained over the twister-head or disk 45 and then around the core strand. The core strand and strand wires are then secured to a suitable take-up and pull-out mechanism (not shown) which, when the machine is set in motion, will pull the strand wires and core through the machine and the twister-head will be rotated to lay the strand wires spirally around the core strand.

The shafts 29 at the head end of the machine are necessary in order to offset the crank-arm members 33 so as to take such crank-arms out of the path of the strand wires from the forwardmost bay.

The spiral arrangement of the strand spool carriers and the arrangement of the sheave collars 41 so as to permit the training of the strand wires parallel and in close proximity to the central shaft 5, are radical departures from the design of stranding machines heretofore used and the arrangement of these parts is essential to the relatively small diameter high speed machine of this invention.

I claim—

1. In a planetary cable stranding machine, a unit comprising a pair of end members, a hollow central shaft journaled in said members, a plurality of spider disks secured on said shaft at spaced intervals so as to form more than three bays, at least three spool carriers mounted in each of said bays and journaled in the spider disks, said spool carriers in each successive bay being offset in the same direction relative to the spool carriers in the preceding bays so that said spool carriers define a spiral path around said central shaft, means for maintaining the transverse axis of said spool carriers in a horizontal plane while said central shaft, spiders and spools are being rotated, spools of strand wires adapted to be journaled in said spool carriers, and means including sheaves carried by said central shaft and apertures in said spiders spaced around and extending parallel

with the longitudinal axis of said central shaft whereby the individual strands from said spools may be trained down from said respective spool carriers within the confines 5 of the next succeeding bay and arranged in parallel relation and in close proximity to said central shaft out of the path of travel of the remaining spool carriers and a twister head at the forward end of said central shaft 10 adapted to twist said strands.

2. In a planetary cable stranding machine, a unit comprising a pair of end members, a hollow central shaft journaled in said end members, a plurality of spider disks secured 15 on said shaft at spaced intervals so as to form more than three bays, spool carriers mounted in each of said bays and journaled in the spider disks, gearing connecting the spool carriers of each bay with the spool carriers of 20 the next succeeding bay; a bearing ring keyed to said central shaft at a point spaced forwardly from the foremost spider disk, a plurality of shafts each of which has one end

journaled in said foremost spider disk and its other end journaled in said bearing ring, 25 gearing connecting the forward ends of the spool carriers in the foremost bay with said shafts, crank members having one end connected to said shafts, other crank members having one end connected to the rear trunnion 30 ends of the spool carriers in the rearmost bay, said cranks connected to said shafts and said cranks connected to the trunnions of the spool carriers in the rearmost bay having their other ends journaled in bearings mounted in crank 35 rings having a center of rotation below the center of rotation of said central shaft a distance equal to the length of said crank members, means for maintaining said crank rings in their off-center position during the rotation of said unit, and means for rotating said central shaft and associated parts.

In witness whereof, I have hereunto signed my name.

EDWARD HAROLD SHOVE.
